RUBBER HEEL

Agostina Santacroce and Anthony Milshow,
Cleveland, Ohio

Application February 9, 1940, Serial No. 318,040

3 Claims. (Cl. 36—35)

Our invention relates to rubber heels and in particular to an improved vacuum type of heel having a recessed center and a slope therein tapered toward its lower end, and having for its main object a cushioning effect whereby the vacuum formed within the recessed center expels air with each step, thus preventing slipping on ice, snow or wet slippery surfaces.

Another object is to provide a cushioning effect and means for expelling stones and other objects from the recessed center of the heel.

These and other objects may be seen and noted from the following specification and its accompanying illustration in which—

15 Fig. 1 is a top plan view of the heel showing the reinforcing fabric and the outer horseshoe shaped tapered rim.

Fig. 2 is a bottom plan view of the heel showing the tapered recess therein.

20 Fig. 3 is a sectional view on lines 3—3 of Fig. 2.
Fig. 4 is a section on lines 4—4 of Fig. 1.

Fig. 5 is a perspective view of the bottom surface showing the suction cups and tapered recess.

25 Fig. 6 is a fragmentary section of the heel secured to footwear.

Again referring to the illustrations, the rubber heel 10 may be a molded form, preferably as shown, in a horseshoe shape, and the inwardly inclined rim 11 may be substantially of the same width around the periphery thereof, forming a

30 concave top surface.

A flat center portion 12 has secured thereon a reinforcing fabric 13 within the inner periphery of the rim 11.

35 An inwardly tapered recess 14 in the bottom surface of the heel 10 has outwardly tapered walls or edges 14a.

The bottom surface of the heel 10 between the inner and outer periphery of the nailing surface

40 10b, is also inwardly inclined.

Suction cups 15, substantially as shown on a raised heel portion 16, are also nail apertures, the head of the nail 18 being countersunk within the cup 15, and other nail holes or apertures may be

45 spaced as shown in Fig. 5.

The heel 10 when secured to suitable footwear will flatten against the heel surface 17 of the said footwear which causes the outer top periphery, of the heel 10, to expand creating a tapered outer edge 10a between the top and bottom 5 peripheries of said heel.

This tapered edge 10a increases the resiliency and creates a greater vacuum within the tapered recess 14 due to the inward pressure of the tapered outer edge 10a against the outward pressure of the inner walls 14a at each tread which forces air or any small substance to be expelled from within the recess 14.

This action prevents slipping when streets are icy or slippery from any cause, and promotes 15 greater safety when walking.

We claim:

1. A rubber heel having a recess in the tread face thereof, and a rim around the back and sides of the recess, the tread surface of the rim 20 being inclined inwardly from its outer edge to said recess, and the bottom surface of the recess being inclined upwardly and forwardly from the rear part of the rim to the front of the heel.

2. A rubber heel having a recess in the tread face thereof, and a rim around the back and sides of the recess, the tread surface of the rim being inclined inwardly from its outer edge to said recess, and the bottom surface of the recess being inclined upwardly and forwardly from the rear 25 part of the rim to the front of the heel, the top surface of the heel being concave and provided with a fabric reinforcement secured to said surface in the concavity.

3. A rubber heel having a recess in the tread face thereof, and a rim around the back and sides of the recess, the tread surface of the rim being inclined inwardly from its outer edge to said recess, and the bottom surface of the recess being inclined upwardly and forwardly from the rear 30 part of the rim to the front of the heel, the rear part of the tread rim having suction cups formed 35 therein.
